US0D1029517S

(12) United States Design Patent (10) Patent No.: US D1,029,517 S
(45) Date of Patent: * Jun. 4, 2024

(54) CHAIR

(71) Applicant: Hangzhou Shinnwa Hometex Co., Ltd., Zhejiang (CN)

(72) Inventor: Jianguo Wu, Zhejiang (CN)

(73) Assignee: Hangzhou Shinnwa Hometex Co., Ltd., Hangzhou (CN)

() Term: 15 Years

(21) Appl. No.: 29/820,030

(22) Filed: Dec. 20, 2021

(30) Foreign Application Priority Data

Dec. 13, 2021 (CN) 202130822149.9

(51) LOC (14) Cl. 06-01

(52) U.S. Cl.

USPC D6/377

Assistant Examiner — Rebecca Lamont

(57) CLAIM

The ornamental design for a chair, as shown and described.

DESCRIPTION

FIG. 1 is a top, front and left side perspective view of a chair showing my new design;

FIG. 2 is a bottom, rear and right side perspective view thereof;

FIG. 3 is a left side view thereof;

FIG. 4 is a right side view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines in the drawings illustrate portions of the chair which form no part of the claimed design. The unshaded area in FIG. 8 forms no part of the claimed design.

1 Claim, 8 Drawing Sheets
